(57) **CLAIM**

The ornamental design for a tray for filling of vials syringes and cartridges for fill and finish machines, as shown and described.

DESCRIPTION

5. Part of tray for filling of vials, syringes and cartridges for fill and finish machines

8. Part of tray for filling of vials, syringes and cartridges for fill and finish machines

5.1 : Right side bottom perspective

5.2 : Top

5.3 : Bottom

5.4 : Front

5.5 : Back

5.6 : Right

5.7 : Left

8.1 : Right side bottom perspective

8.2 : Top

8.3 : Bottom

8.4 : Front

8.5 : Back

8.6 : Right

8.7 : Left

The broken lines and the half-tone shaded area within the broken lines depict portions of the tray for filling of vials syringes and cartridges for fill and finish machines that form no part of the claimed design.

The characteristic features of the designs lie in the shape of the product. Fig. 5.1 is bottom perspective view of a part of tray for filling of vials, syringes and cartridges for fill and finish machines; Fig. 5.2 is a top view thereof; Fig. 5.3 is a bottom view thereof Fig. 5.4 is a front view thereof Fig. 5.5

(Continued)

is a back view thereof; Fig. 5.6 is a right side view thereof and Fig. 5.7 is a left side view thereof. Fig. 8.1 is a bottom perspective view of a part of a tray for filling of vials, syringes and cartridges for fill and finish machines; Fig. 8.2 is a top view thereof; Fig. 8.3 is a bottom view thereof Fig. 8.4 is a front view thereof; Fig. 8.5 is a back view thereof Fig. 8.6 is a right side view thereof and Fig. 8.7 is a left side view thereof.
